UNITED STATES PATENT OFFICE

MARCO BACCICH, OF FIUME, AND CARLO DE-FILIPPI, OF MILAN, ITALY

HYDROPNEUMATIC RESERVOIR FOR PETROL FUELS AND THE LIKE

Application filed March 21, 1928, Serial No. 263,826, and in Egypt March 22, 1927.

It is known that petrol tanks employed at the present time operate by a pressure of atmospheric air obtained in the interior of the device by means of a large hand pump so as to deliver the supply liquid to the various vaporizers and to give the petrol vapour a sufficient velocity for it to mix with the outside air and to secure complete combustion.

Such devices present however the following disadvantages:

1. The small losses of air from one of the valves of the said pump or from the tank prevent the latter from working. This occurs in the case, for example, when the piston washer becomes dried on account of the heat developed by the compression of the air making it no longer possible to obtain a sufficient quantity of air and consequently a sufficient pressure in the tank.
2. The difficulty of maintaining the pumping by hand at a constant pressure is another of the considerable disadvantages because the said pressure varies according as the air chamber varies in size and according as the liquid (petrol) which is situated therein varies in quantity.

The object of the present invention is to provide a hydropneumatic petrol tank arrangement adapted to give the necessary velocity to the petrol supplying the various burners in use, for example, for hot baths, heating rooms, for heaters, for lighting lamps, for kitchens, for soldering lamps, etc.

This is obtained by employing the pressure which exists in the city water pipes, without the possibility of damaging in any way the said pipes or interfering with their normal operation.

The accompanying drawing illustrates by way of example an embodiment of the subject of the present invention and in particular it represents a hydropneumatic tank viewed in medial sectional elevation.

In this drawing, —1— is the tank made of metal (iron, copper etc.); —5— is a wall dividing the tank into two chambers of calculated size; —3— is the chamber reserved for the petrol; —4— is a tube for protecting and guiding the stem of the float —7—; and the hollow valve —7”—, —8— is a pipe es-

tablishing communication between the small chamber —8— and the chamber —3—; —6— is the petrol supply opening; —9— is a manometer; —10— is a tube for drawing petrol from the bottom of the said chamber or tank; —14— is a glass tube indicating the level of the petrol; —12— is a tap for admitting the city water into the chamber —3—; —13— is the discharge tap for the same; —15— is a cock establishing communication with various burners.

The operation of the device is as follows:

Assuming the tank to be in a vertical position and completely empty, the chamber —3— is filled with petrol through the filling hole —6— which is then closed hermetically. The emptying tap —13— being closed city water is admitted through the tap —12—. The atmospheric air which was stored inside the tank —3— is compressed as the water which is admitted into the said tank rises. When the desired pressure is obtained, which will be indicated by the manometer —9—, the admission of water may be cut off by closing the tap —12— although the latter may be left open continually. It is to be noted that the pressure of the city water in rooms or shops may be inversely proportional to their height above the ground, being in the region of 1 kg. upon the fifth floor and 4½ kg. on the ground floor; with a mean pressure of 1½ kg. per square centimetre the pressure remains always more than sufficient for the operation of the apparatus in question.

The air thus compressed passes through the pipe —4—, hole —16— and pipe —8— into the chamber —3— reserved for the petrol, thus exerting a pressure on the latter.

This pressure will be indicated on the manometer —9—. The petrol thus compressed will be ejected through the tube —10— and through the small tap —15— in order to atomize at the various burners.

In order to remove the compression and provide a supply of petrol the tap —12— is closed (that is if it is open) and the discharge tap —13— of the water is opened. The filling plug in the hole —6— is removed and the petrol is poured in as desired. The filling hole —6— is then closed and also

the tap —13—, the latter remaining open during the whole filling in order to give the water time to run out and be replaced by atmospheric air.

5 —7— is a safety float valve which operates in the following manner:

If before or after the admission of the petrol the tap —6— has accidentally not been closed and the tap —12— is opened the water in this case would fill the tank —3— as it would encounter no resistance on the part of the atmospheric air. The float —7— and the float valve —7''— would be raised and would close the communication orifice 15 —16— thus preventing the water from entering the chamber —3— containing the petrol and the two liquids becoming mixed together.

The hollow valve —7''— is provided with 20 an orifice —2— for the passage of the compressed air intended in the case of a lifting movement to produce the closure of the orifice —16—.

It is obvious that the apparatus in question may be constructed in various forms 25 while preserving the basic principle of operation, that is to say that the two tanks may be arranged one inside the other over the whole or a part of the total length, or one 30 outside the other and that the position of the members may be changed.

Having now particularly described and ascertained the nature of our said invention and in what manner the same is to be performed, we declare that what we claim is:—

1. A liquid elevator comprising a tank 40 provided intermediate its ends with a partition to form two chambers in superposed relation therein, a centrally disposed tubular member in the upper chamber and opening into the lower chamber, an oil outlet in the upper chamber, means for admitting water under pressure into said lower chamber, an outlet for the water at the lower part 45 of the tank, a conduit connecting said upper chamber with the interior of said tubular member, a float in said lower chamber, and a valve in said tubular member, said valve being actuated by said float to close said conduit when a predetermined amount of water 50 has been admitted to said lower chamber.

2. An elevator for petrol fuels or like comprising a tank provided intermediate its ends with a partition to form two chambers in superposed relation therein, the under chamber being designed to receive water whilst the upper chamber serves as a reservoir for the petrol, a small air chamber disposed upon said petrol chamber, a pipe establishing communication between the small air chamber and the petrol chamber, a tubular member centrally disposed in the petrol chamber and opening at its under end into the water chamber whilst it communicates 55 at its upper end with the air chamber through

an orifice placed at the bottom of the latter, means for admitting water into the water chamber, a tap for discharging water from said water chamber, means for admitting petrol into the petrol chamber, a cock for the 70 outflow of the petrol from said petrol chamber, a float in the water chamber, and a valve in said tubular member, said valve being actuated by said float to close the air chamber when a predetermined amount of water 75 has been admitted to the water chamber.

In testimony whereof we affix our signatures.

MARCO BACCICH.
CARLO DE FILIPPI.
